UNITED STATES PATENT OFFICE.

HARRY WIARD, OF SYRACUSE, NEW YORK.

CULTIVATOR.

SPECIFICATION forming part of Letters Patent No. 557,465, dated March 31, 1896.

Application filed October 4, 1895. Serial No. 564,647. (No model.)

To all whom it may concern:

Be it known that I, HARRY WIARD, of Syracuse, in the county of Onondaga, in the State of New York, have invented new and useful 5 Improvements in Cultivators, of which the following, taken in connection with the accompanying drawings, is a full, clear, and exact description.

My invention relates to improvements in 10 cultivators, and has for its object the production of a device which is simple in construction, readily adjustable, and highly efficient in operation; and to this end it consists, essentially, in the construction of the frame- 15 bars and the tooth-supports.

It also consists in the detail construction and arrangement of the parts of the cultivator, all as hereinafter fully described, and pointed out in the claims.

20 In describing this invention reference is had to the accompanying drawings, forming a part of this specification, in which like letters indicate corresponding parts in all the views.

25 Figures 1 and 2 are respectively a top plan and side elevation of my improved cultivator. Fig. 3 is a vertical section, partly in elevation, taken on line 3 3, Fig. 1. Fig. 4 is a horizontal detail section taken on line 4 4, Fig. 2; and 30 Fig. 5 is a top plan view of the detached central frame-bar of the cultivator.

The frame of my cultivator preferably consists of the central bar a , adjustable side bars $a' a'$, and spreader-bars a^2 . Suitable handles 35 a^3 are secured to the bar a , and an actuating-lever a^4 is connected by a link a^5 to a head a^6 , which is movable lengthwise of the bar a and is connected to the spreader-bars for operating the same. A locking-lever a^7 is hinged 40 at one extremity to a standard a^8 , projecting upwardly from the bar a , and is provided at its opposite end with teeth for engaging a shoulder a^9 upon the head a^6 , and thereby holding said head in its adjusted position. A 45 spring a^{10} holds the locking-lever a^7 in operative position, and a hand-lever a^{11} , pivoted to the actuating-lever a^4 , is suitably connected to the locking-lever a^7 for withdrawing the same from operative position against the action of the spring a^{10} .

The connection between the levers $a^7 a^{11}$ may be of suitable construction, but prefer-

ably consists of a link a^{12} , having one end hinged to the lever a^7 and its upper end passed through an upright slot a^{13} in the lever a^{11} and 55 provided with a longitudinally-adjustable shoulder a^{14} , arranged in a substantially horizontal aperture a^{15} in the lever a^{11} , which is provided with upper and lower faces for engaging the shoulder a^{14} . The adjustable connection of the lever a^{11} and the link a^{12} is quite 60 important, as the ready adjustment of the operation of the locking-lever a^7 is thereby effected by very simple means easily operated when desired.

65 The central frame-bar a consists of separate sections having front and rear contiguous portions $a^{16} a^{17}$ and outwardly-extending portions $a^{18} a^{19}$ arranged in advance and at the rear of the front contiguous portions a^{16} . The separate sections of the bar a are firmly secured together and their peculiar construction forms apertures $a^{20} a^{21}$ in front and at the rear of the front contiguous portions a^{17} of said sections. The side frame-bars $a' a'$ are formed with engaging faces a^{22} , arranged one in advance of the other and disposed in convex and concave planes extending lengthwise of said frame-bars.

70 B B are the teeth of my improved cultivator, which are preferably composed of spring material and are formed substantially C-shaped, and C C are tooth-supports for securing said teeth to the frame-bars $a' a'$. As best seen at Fig. 1, only one tooth is secured 75 to the frame-bar a , and the tooth-support C for said tooth is secured to the front contiguous portions a^{16} of the separate sections of said frame-bar, and consequently the front bow portion and rear extremity of said tooth 80 are arranged in advance and at the rear of said contiguous portions. It will also be noted upon reference to Fig. 1 that the front bow portions and rear extremities of the teeth secured to the frame-bars a' are arranged, 85 respectively, in advance and at the rear of the curved engaging faces a^{22} .

90 The tooth-supports C preferably consist of opposite sections $c c'$, having the adjacent faces of their lower ends provided with 95 grooves c^2 for receiving the attaching ends of the teeth B and their upper ends arranged on opposite sides of the frame-bars and formed with upper and lower shoulders c^3 for engag-

ing the upper and lower edges of said frame-bars. The sections of the tooth-supports secured to the side bars a' are formed with concave and convex engaging faces $c^4 c^5$, bearing 5 against the corresponding faces a^2 of said frame-bars. The lower ends of the tooth-support sections are securely clamped against the attaching ends of the teeth B by clamping-bolts c^6 , and the upper ends of said sections 10 are held in their adjusted position by clamping-bolts c^7 , passed through the frame-bars and having their opposite ends arranged in slots c^8 , formed in the upper ends of the tooth-support sections and extending lengthwise of 15 said frame-bars.

It will be obvious that owing to the peculiar construction of the engaging faces of the side frame-bars a' and the tooth-supports mounted thereon the inclination of the digging-points of the corresponding teeth is varied, as 20 said tooth-supports are adjusted lengthwise of the line of draft.

D is the land-wheel for the cultivator, and E a support for said land-wheel, consisting of 25 opposite sections or bars arranged on opposite sides of the front bow portion b of the central tooth B and having their rear ends pivoted at e to the frame-bar a . Interposed between the central portions of the bars of said support is 30 an upwardly-projecting arm e' , provided with perforations for receiving a pin, (not illustrated,) which is passed through a perforation e^2 in said support when hand adjustment thereof is not desired. The support E is ad- 35 justed by an actuating-lever E' , which is connected thereto by a link E^2 , and the lever E' is formed with a downturned front end e^3 and is provided at its rear end with a locking-dog e^4 , which engages a toothed segment e^5 .

40 The operation of my improved cultivator will be readily understood upon reference to the foregoing description and the accompanying drawings, and it will be particularly noted that the entire surface over which it is mov- 45 able is uniformly and thoroughly worked, the draft equally distributed at all points, the teeth firmly secured in position, and the inclina- 50 tion of their digging-points readily adjusted, and the land-wheel easily adjusted without precluding the use of a central tooth.

Having thus fully described my invention, what I claim as new, and desire to secure by Letters Patent, is—

1. In a cultivator, the combination of a 55 frame-bar provided with a curved engaging face, a spring-tooth, a tooth-support secured to the tooth and provided with a face bearing against the engaging face of the bar, and a slot extending lengthwise of the bar, and a 60 clamping-bolt passed through said slot for adjustably securing the tooth-support to the bar, substantially as and for the purpose specified.

2. In a cultivator, the combination of a 65 frame-bar, a spring-tooth, a tooth-support consisting of opposite sections having grooves in the adjacent faces of their lower ends for re-

ceiving and supporting the spring-tooth and having their upper ends movable lengthwise of the frame-bar, and a clamping-bolt for se- 70 curing the tooth-support to the bar, substan- tially as and for the purpose set forth.

3. In a cultivator, the combination of a side frame-bar provided with engaging faces ar- 75 ranged one in advance of the other and dis- posed in convex planes extending lengthwise of the frame-bar, spring-teeth formed sub- stantially C-shaped and having their front bow portions and their rear extremities ar- 80 ranged in advance and at the rear of the engag- ing faces, tooth-supports each consisting of opposite sections having grooves in the adja- cent faces of their lower ends for receiving and supporting the corresponding teeth, and having their upper ends provided with shoul- 85 ders for engaging the frame-bar, concave en- gaging faces bearing against the convex en- gaging faces of the frame-bar and slots ex- tending lengthwise of said frame-bar, clamp- ing-bolts for drawing the lower ends of said 90 sections together, and clamping-bolts passed through said frame-bar and slots for drawing together the upper ends of said sections and securing the same to the frame-bar, substan- tially as described.

4. In a cultivator, the combination of a 95 frame provided with a longitudinally-extend- ing substantially central aperture, and a spring-tooth supported on the frame and ar- ranged within said aperture substantially co- 100 incident with a line drawn through the lon- gitudinal center of the frame, substantially as and for the purpose specified.

5. In a cultivator, the combination of a 105 frame-bar having an inwardly-deflected por- tion and outwardly-deflected portions in ad- vance and at the rear of the former portion, a tooth-support secured to the inwardly-de- 110 flected portion, and a curved spring-tooth se- cured to said support and having its front bow portion and its rear extremity arranged in advance and at the rear of said inwardly- 115 deflected portion of the bar and at the inner sides of the outwardly-deflected portions thereof, substantially as and for the purpose set forth.

6. In a cultivator, the combination of a 120 frame-bar consisting of separate sections hav- ing front and rear contiguous portions secured together, and outwardly-extending portions 125 arranged in advance and at the rear of the front contiguous portions for forming ap- 130 pertures in said bar, a tooth having its front bow portion and its rear extremity passed between said outwardly-extending portions, and a tooth-support secured to the front contiguous portions of the frame-bar sections and to the tooth, substantially as and for the purpose specified.

7. In a cultivator, the combination of a 130 frame-bar having an inwardly-deflected por- 135 tion and outwardly-deflected portions in ad- vance and at the rear of the former portion, a tooth-support secured to the inwardly-de-

flected portion, and a curved spring-tooth secured to said support and having its front bow portion and its rear extremity arranged in advance and at the rear of said inwardly-deflected portion of the bar and at the inner sides of the outwardly-deflected portions thereof, a land-wheel support having separate sections arranged on opposite sides of said tooth, and an actuating-lever connected to said land-wheel support for operating the same, substantially as described.

8. In a cultivator, the combination of a frame-bar consisting of separate sections having front and rear contiguous portions secured together, and outwardly-extending portions arranged in advance and at the rear of the front contiguous portions for forming apertures in said bar, a tooth having its front bow portion and its rear extremity passed between said outwardly-extending portions, and a tooth-support secured to the front contiguous portions of the frame-bar sections and to the tooth, a land-wheel support having separate sections arranged on opposite sides of said tooth, an actuating-lever having a depending arm pivoted to the frame-bar, and a connection or link consisting of separate sections arranged on opposite sides of said tooth and having their front extremities pivoted to the land-wheel support and their rear extremities to said depending arm, substantially as and for the purpose described.

9. In a cultivator, the combination of frame-bars, a movable head and an actuating-lever for moving said head; with a movable locking-lever or bar having one end hinged and the other end engaged with said head, a hand-lever pivoted to the actuating-lever, and a link having one end connected to the locking-lever and its other end adjustably connected to said actuating-lever, substantially as set forth.

10. In a cultivator, the combination of frame-bars, a movable head, and an actuating-lever for moving said head; with a movable locking lever or bar having one end hinged and the other end engaged with said head, a hand-lever pivoted to the actuating-lever and provided with an upright slot and a substantially horizontal aperture, a link having one end connected to the locking-lever and its other end passed through the slot and aperture, and a shoulder arranged in said aperture and movable lengthwise of the link, substantially as described.

In testimony whereof I have hereunto signed my name, in the presence of two attesting witnesses, at Syracuse, in the county of Onondaga, in the State of New York, this 3d day of February, 1894.

HARRY WIARD.
